UNITED STATES PATENT OFFICE.

JOHN S. DAVIS, OF ATTLEBOROUGH, MASSACHUSETTS.

ACOUSTIC TELEPHONE.

SPECIFICATION forming part of Letters Patent No. 233,215, dated October 12, 1880.

Application filed April 8, 1880. (No model.)

To all whom it may concern:

Be it known that I, JOHN S. DAVIS, of Attleborough, in the county of Bristol and State of Massachusetts, have invented a new and 5 useful Improvement in Acoustic Telephones; and I hereby declare that the following is a full, clear, and exact description of the same, reference being had to the accompanying drawings, forming part of this specification.

10 This invention has reference to an improvement in that class of telephones in which a diaphragm is vibrated by the voice, and the vibration transmitted by means of a wire connected with the diaphragm, and also to another 15 diaphragm, and the vibrations reproduced, so that conversation can be carried on between two points.

10 The object of this invention is to improve the construction and utility of such a telephone-line.

The invention consists in the peculiar method of suspending and securing the wire; also, in the peculiar construction and arrangement of the sound producing and receiving device, and 25 also in the peculiar construction and arrangement of a call for an acoustic telephone, as will be more fully set forth hereinafter.

Figure 1 is a view of the transmitting and receiving instrument, showing also a pivoted 30 call, which can be swung over the aperture of the transmitter. Fig. 2 is a sectional view of the transmitting and receiving instrument, showing the sheet-metal diaphragm and the connecting-wire, also the reed-call. Fig. 3 is 35 a perspective view, showing the line-wire, the manner of supporting the same, as also the manner of connecting the receiving and transmitting instrument with the line-wire. Fig. 4 is an enlarged view, illustrating a preferred 40 mode of supporting the line-wires.

In the drawings, *a* represents a circular disk, having on its face a concaved or dished depression, *a'*, in the center of which is the circular opening *a²*. *b* is a circular disk, also 45 provided with a central hole.

Both the disks *a* and *b* have a narrow edge at their periphery-level, so as to form a bearing for the diaphragm *c*, and the rest of the inner faces next the diaphragm are beveled to 50 the central holes, as is shown in Fig. 2.

The diaphragm *c* is a circular disk of sheet

metal, and I prefer for this a sheet of soft brass, as it will produce a fuller note than harder metal and avoids the creaking noise incidental to hard-metal disks.

55

d is a button, to which the wire *e* is connected so as to bear with its rounded side against the diaphragm by reason of a slight strain on the wire *e*, which is connected with the line-wire *f*, as shown in Figs. 2 and 3, between two fastenings. By securing the wire *e* to the wire *f* any desired tension can be readily secured not affected by the strain on the line-wire or by action of wind on the same.

60 *g* is a reed-call pivotally connected, so that it may be quickly placed over the central aperture, and the vibration of the reed in the call will produce a strong vibration of the diaphragm, so that the reproducing-diaphragm on the other end of the line will give a loud 65 call, which can be heard a great distance, and is so different from ordinary sounds that the attention is at once directed to the same.

70 The line-wire *f* may extend a long distance, and be supported at intermediate points by 75 means of supports such as are shown in Fig. 4. Such a wire requires strong connections on the ends, and when such ends are directly connected with the diaphragm of an acoustic telephone the strain prevents the free vibrations of the diaphragm.

75 To avoid this difficulty I firmly secure the ends of the wire beyond the point at which the transmitter is placed. I now secure the wire *e* connected with the diaphragm to the wire *f*, and spring said wire *f* slightly, so that the spring of the diaphragm will be sufficient to regain its natural plane, and a slight effort of the voice—such as a whisper—will communicate the vibrations to the wire, to be reproduced at 80 the other end. By this arrangement more than two transmitting and receiving instruments may be placed on one line of wire.

85 To transmit the vibrations clearly and fully I suspend the wire by means of a fibrous cord, 90 *k*, from any support, *i*. I prefer a slightly-twisted hempen cord, but other fibrous material may be used.

95 *l* is a union-piece of metal, to which the ends of the wire are connected, and to which the cord *k* is also connected, as shown in Fig. 4. It may be made of light sheet or cast metal,

or it may be formed of a piece of wire; but the connection of the two wires *ff* with the piece *l* must be such as will not interfere with the vibrations of the wire.

- 5 The disks *a* and *b*, forming the transmitting and receiving instrument, I prefer to make of some light resonant wood. The diaphragm *c* bears on the outer edge, and the two disks are secured together with the diaphragm between 10 them by means of nails or screws. The beveled inner faces of the disks *a* and *b* allow the diaphragm to vibrate at the center, and the beveled surfaces allow the air impelled against the diaphragm *c* to act by repulsion on a larger 15 part of the diaphragm, and I find that with such beveled surfaces the enunciation of speech is more fully reproduced, giving a fuller note and clearer reproduction of the timbre of the voice.
- 20 My improved acoustic telephone can be used for considerable distances and can be branched off to more than the two points at each end of the line. When a call is made by the reed and answered the reed is swung on one side, and 25 conversation can be held between distant points by standing before the transmitter and speaking toward the opening *a*². Any answer can be distinctly heard without placing the ear near the transmitter, and neither battery 30 nor magnets are used, the whole being cheap and simple in construction.

Having thus described my invention, I claim as new and desire to secure by Letters Patent—

1. In a telephone, the combination, with the 35 transmitter or receiver, of a reed secured to a pivoted arm and adapted to be swung into line with said instrument, so that such reed shall be supported independently of said instrument and out of contact therewith, but in alignment 40 with its opening, substantially as described.

2. In an acoustic telephone, the method of securing the line-wire, the same consisting in securing the ends of the wire, as described, suspending the wire by means of fibrous material, and connecting the diaphragms to the line-wire by means of the wire *e*, as described.

3. In an acoustic telephone, the combination, in the transmitting and receiving instruments, of the disk *a*, concaved at *a*', having a 50 central opening, *a*², and a flattened rim dished inwardly toward the central opening, and a disk, *b*, having a central opening and a flattened rim dished inwardly toward the central opening, a soft-metal diaphragm secured between said flattened rims of said disks, the button *d*, and the attached wire *e*, secured to the main or line wire *f* at a point between the point of attachment of said line-wire below the instrument and its point of suspension above 55 such instrument, all constructed and arranged to operate substantially as described and shown.

JOHN S. DAVIS.
